[57] **CLAIM**

The ornamental design for a combined trash and recyclable garbage compacting device, as shown and described.

DESCRIPTION

FIG. 1 is a front elevational view of a combined trash and recyclable garbage compacting device showing my new design, the rear elevational view being a mirror image;

FIG. 2 is an exploded rear elevational view thereof, the exploded front elevational view being a mirror image;

FIG. 3 is a left side elevational view thereof;

FIG. 4 is a right side elevational view thereof;

FIGS. 1-4 are shown fragmented to indicate that, for ease of illustration, a precise length of the article is not claimed.

FIG. 5 is a top plan view thereof; and,

FIG. 6 is a bottom plan view thereof.
